CLAIM

The ornamental design for a direct current gear motor box with side bracket, as shown and described.

DESCRIPTION

FIG. 1 is a top plan view of a direct current gear motor box with side bracket showing our new design.

FIG. 2 is a right side elevational view thereof.

FIG. 3 is a left side elevational view thereof.

FIG. 4 is a bottom plan view thereof.

FIG. 5 is a rear end elevational view thereof.

FIG. 6 is a front end elevational view thereof.

FIG. 7 is a rear, bottom, right perspective view thereof; and,

FIG. 8 is a rear, top, right perspective view thereof.
